UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

FARE-BOX.

1,032,842.

Specification of Letters Patent. Patented July 16, 1912.

Application filed October 12, 1908. Serial No. 457,742.

To all whom it may concern:

Be it known that I, GEORGE B. KOHLER, a citizen of the United States, residing in Philadelphia, Pennsylvania, have invented 5 certain improvements in Fare-Boxes, of which the following is a specification.

My invention relates to certain improvements in fare-boxes adapted to be used upon passenger cars and particularly of the type 10 in which a passenger pays the fare on entering the car.

The object of my invention is to so construct the box that on the discharge of the fare from the receiving section into the fare 15 receptacle it will be registered.

The invention also relates to details of construction of the mechanism for actuating the discharge device.

In the accompanying drawings—Figure 1 20 is a side view, partly in section, illustrating a portion of the fare box showing my improvements; and Fig. 2 is a section on the line 2—2, Fig. 1.

A is a fare box having a receptacle B, 25 shown by dotted lines in Fig. 1. This receptacle is mounted within a movable drawer so that when the drawer is opened the receptacle can be detached. This particular form of receptacle is fully set forth 30 in an application for patent filed even date herewith.

C is a fare receiving section of the fare box mounted on a section A' containing the discharge mechanism and the registering 35 mechanism in the present instance. The fare receiving section has glazed sides c and glazed inclined deflectors c' for the passage of the fare.

The bottom of the fare receiving section 40 is closed by a platform D and pivoted at d to the platform is a curved closing plate D', so that when the platform is tilted the closing plate will close the opening in the bottom of the fare receiving section and no 45 fares can pass into the receptacle without first being retained by the plate D.

E is an operating lever pivoted in the present instance at e and having an arc e' attached to an arm F by a rod E'. The 50 arm is mounted on a rock shaft F' on which is mounted the closing plate D'. On the shaft is an arm F² connected by a link f to a lug d' on the underside of the platform D so that each time the lever is operated the fare is discharged from the re-

ceiving section into the fare receptacle in the body of the fare box.

G is a register of any of the ordinary types; the numbers on this register can be seen through the glazed opening a in the 60 section A'. The register is actuated from the lever E. In the present instance the rod E' has a slotted lug e² in which is a pin g carried by an arm G² which is connected to the operating mechanism of the 65 register, so that when the lever E is moved the registering mechanism will be moved forward one number. I also provide a bell for the announcement of the registration of a fare, this bell H being mounted on a stem 70 h projecting from the casing A² carrying the discharge mechanism of the fare box.

I is a carrier pivoted at i, and projecting from this carrier is a clapper i'; a spring i² tends to hold the carrier in the fixed position and this carrier is actuated by a pivoted pawl f' on an arm F. The pawl is projected by a spring f², so that as the lever E is moved to discharge the fare into the fare receptacle the pawl f' trips the carrier I and causes the clapper to strike the bell.

I claim:

1. The combination in a fare box, of a body portion containing a receptacle for the 85 fares; a fare receiving section; a pivotally mounted discharge device for closing the bottom of the fare receiving section; an operating lever pivotally mounted on the body portion; a pivoted lever connected to the 90 discharge device; a rod connecting one arm of the lever with the operating lever; a registering mechanism; a slotted arm on the registering mechanism; a pin on the connecting rod extending into the slot in the 95 arm so that, as the lever is operated to actuate the discharge device, the registering mechanism will be actuated.

2. The combination in a fare box, of a body portion containing a receptacle for the fares; a fare receiving section mounted thereon; a discharge device; a shaft; an extension on the shaft to which the discharge device is pivoted; an arm on the 100 shaft; a link connecting the arm with the discharge device some distance from its pivot; an operating arm, also on the discharge device; an operating lever pivoted to the body portion; a rod connecting the 105 operating lever with the operating arm of 110

the shaft; a lug having a pin on the said rod; a swinging arm on the registering mechanism having an angular slot into which the pin extends; a ratchet wheel on the registering mechanism; and a pawl on said swinging arm engaging said ratchet wheel.

In testimony whereof, I have signed my name to this specification, in the presence of two subscribing witnesses.

GEORGE B. KOHLER.
